FRIDOLIN W. KURTZ, OF NEW YORK, N. Y.

ELECTRIC SWITCH

983,908.

Specification of Letters Patent. Patented Feb. 14, 1911.

Application filed October 12, 1909. Serial No. 522,291.

To all whom it may concern:

Be it known that I, FRIDOLIN W. KURTZ, a subject of the German Emperor, and a resident of the borough of Manhattan, in the county, city, and State of New York, have invented a certain new and useful Improvement in Electric Switches, of which the following is a specification.

This invention relates to that form of electric switch which is employed to bring into and to carry out of operation in any required order or sequence either the individual lights of a series, or the individual circuits of lights, when a number of circuits are employed, and is especially useful in halls, offices, and stores, as well as in hotels and apartment houses, where it is desirable to vary at different times the number of the individual lights in the one case or the individual circuits in the other, that are to be operated; the object of the invention being to simplify the construction of switches of this character, and to produce a device, which, while more efficient in operation than those heretofore employed, shall, at the same time, be more convenient in use.

To these ends the invention consists, in certain peculiarities of construction and combinations of parts, of which the form preferred in practice will first be hereinafter specifically described, and the features of the invention then pointed out in the subjoined claims.

Referring to the accompanying drawings, which form a part of this specification, Figure 1, is a plan view of an electric switch embodying my invention, with parts broken away for convenience of illustration and showing a number of electric lights with their appropriate electric circuits; Fig. 2, an edge view thereof partly in section and partly in elevation, the sectional portion being taken in the plane $\alpha\alpha$ of Fig. 1, and looking in the direction of the arrows in that figure; Fig. 3, a side elevation of the circuit closing arm with parts broken away for convenience of illustration; Fig. 4, a transverse section of the circuit closing arm taken in the plane yy of Fig. 3, and looking in the direction of the arrows in that figure; Fig. 5, a plan view of a portion of the circuit closing arm broken away; Fig. 6, is a transverse section of a circuit controlling arm of a slightly modified construction, also taken in the plane yy of Fig. 3 and similarly looking in the direction of the arrows in that

figure, and Fig. 7, a vertical transverse section of the base and rings of a slightly modified construction, likewise taken in the line $\alpha\alpha$ of Fig. 1, and showing a portion of the circuit closing arm and the stud upon which it is mounted in elevation.

In all the figures, like letters of reference are employed to designate corresponding parts.

A indicates a suitable base; and B, B^1 , B^2 , and B^3 indicate a series of rings which are fixedly secured to the base A in concentric relationship to one another, with a narrow space intervening between the adjacent rings. In the construction of this base any appropriate material that is suited for the purpose may be employed. It is preferred however to construct it of slate, glass, fiber or the like, and to provide it with apertures a , through which, and appropriate screws, it may be secured in place. The rings B, B^1 , B^2 , and B^3 , on the other hand, are constructed of some electricity conducting material, and may be secured to the base in any convenient manner, as, for instance, by screws b . When the base A is constructed of wood or other similar material these rings will preferably be insulated therefrom by appropriate strips of insulating material b^1 interposed between them and the base, as shown in Fig. 7. On the other hand, when the base is constructed of slate or other electricity non-conducting material, these rings will be preferably secured directly thereto, without the intervention of any intervening strips of insulating material. As thus supported these rings B, B^1 , B^2 , and B^3 , are respectively provided with series of contacts s , s^1 , s^2 , etc., t , t^1 , t^2 , etc., u , u^1 , u^2 , etc., and v , v^1 , v^2 , etc., which extend upward from their upper surfaces for a short distance in the shape of studs, and are so disposed with respect to each other in the different rings that they may be connected in various combinations, as may be desired.

Secured within the base A, in axial relationship to the rings B, B^1 , B^2 , and B^3 , is a hollow stud C, which extends downward through a suitable orifice a^1 formed in the base and is firmly clamped therein by a nut c , threaded upon its lower end and co-operating with a shoulder c^1 with which the stud is provided. This stud C is preferably constructed of some suitable electricity conducting material and receives and supports at its lower end an electrical terminal c^2 ,

which, in the form of the invention shown in the drawings, is constructed in the form of a ring, and, clamped between the nut c on the lower end of the stud and the base A, 5 is provided with a binding post c^3 for reception of the electric conductor E through which the current for supplying the lamps or circuits is passed. As thus arranged and connected, the stud C receives and supports 10 a circuit closing arm D, which is rotatively mounted thereon, and, extending outward over and across the rings B, B¹, B², and B³, is constructed of a suitable electricity conducting material and is equipped on its under side with a series of contacts d , d^1 , d^2 , and d^3 , corresponding in number with the 15 number of rings employed, with these contacts so disposed therein as to register with their respective co-operating contacts s , s^1 , s^2 , etc., t , t^1 , t^2 , etc., u , u^1 , u^2 , etc., and v , v^1 , v^2 , etc., in the rings B, B¹, B², and B³, when 20 brought over them. With the circuit closing arm thus mounted, it is free to be rotated upon the pivot C to bring its contacts d , d^1 , d^2 , and d^3 into engagement with their respective co-operating contacts in the 25 rings B, B¹, B², and B³; and in order to provide for its rotation when required this arm is provided at its outer free end with a 30 handle d^4 , which is either constructed of some electricity non-conducting material or is insulated therefrom.

In the construction of the contacts d , d^1 , d^2 , and d^3 , various forms may be adopted. 35 In Figs. 2, 3, 4, and 5, however I have shown them as constructed in the form of short studs extending downward from the under surface of the circuit closing arm, while in Fig. 6 I have shown them as formed in the 40 shape of downwardly curved springs, but these are merely illustrative and other forms may be employed if so desired and the switch operate with equal efficiency. The circuit closing arm being thus provided with the 45 contacts d , d^1 , d^2 , and d^3 , and mounted on the stud C is electrically connected with the conductor E, and whenever any one or more of its contacts is or are engaged with a contact or contacts on the rings B, B¹, B², and 50 B³, the ring or rings in which this last mentioned contact or these last mentioned contacts is or are arranged will become electrically energized and serve as a conductor or as conductors, as the case may be, for the 55 current as it is passed forward to the point or points where it is to be applied.

Connected with the respective rings B, B¹, B², and B³, are electric conductors F, F¹, F², and F³, which lead to the lamps that are to 60 be operated. In some instances a number of lamps may be operated from each conductor, which, in that case, may be arranged in series or in multiple. For purposes of illustration however, I have shown but a 65 single lamp operated from each, and this

is connected in multiple with the return conductor E¹, with the lamp f arranged in circuit with the conductor F, the lamp f^1 arranged in circuit with the conductor F¹, the lamp f^2 arranged in circuit with the conductor F², and the lamp f^3 arranged in circuit with the conductor F³, the several lamps being connected across from their respective supply conductors F, F¹, F², and F³ to the return conductor E¹ through appropriate 70 connections f^4 , f^5 , f^6 , and f^7 , as shown in Fig. 1. As thus arranged, whenever the conductors E and E¹ are properly connected in circuit and the circuit closing arm D is so rotated as to bring one or more of its 75 contacts d , d^1 , d^2 , d^3 into engagement with one or more of the contacts on the rings B, B¹, B², B³, the current will pass upward through the stud C, thence outward through the circuit closing arm D to and through the 80 ring or rings containing the contact or contacts with which its own contact or contacts is or are engaged, thence outward through the conductor or conductors F, F¹, F², F³, with which the ring or rings is or are connected, thence to and through the respective lamp or lamps answering to that conductor or those conductors, to the return conductor E¹ and the lamp or lamps thus in circuit thereby operated. This operation of the 85 lamp or lamps will continue so long as the contact or contacts of the circuit closing arm are in engagement with the appropriate contact or contacts on the ring or rings B, B¹, B², B³ and the circuit or circuits remains or 90 remain closed, but will be interrupted the moment the circuit or circuits is or are broken by the removal of the contact or contacts on the circuit closing arm from engagement with its or their co-operating contact or contacts on the ring or rings. In other words, to illustrate, whenever it is desired, for instance, to operate all the lamps connected in circuit with the conductors F, F¹, F², and F³, the circuit closing arm D will be swung 95 100 105 on the pivot C until its contacts d , d^1 , d^2 , and d^3 are brought into engagement with the contacts s , t , u , and v , on the respective rings B, B¹, B², and B³, when the circuits through such lamps will be closed and they thereby 110 115 120 125 brought into operation. Or, whenever it is desired to bring only the lamps connected in circuit with the conductors F, F², and F³ into operation, then the circuit closing arm will be rotated on the pivot C until the contacts d , d^2 , and d^3 carried by it are brought into engagement with the contacts s^1 , u^1 , and v^1 on the respective rings B, B², and B³, when the circuits through those conductors will be closed and the lamps f , f^2 , and f^3 125 similarly brought into operation. The same is also true whenever it is desired to bring into operation the lamps connected in circuit with the conductors F, F¹, and F², the 130 circuit closing arm will then be swung on

the pivot C until its contacts d , d^1 , and d^2 are brought into engagement with the contacts s^2 , t^1 , and u^2 on the respective rings B , B^1 , and B^2 , when the circuits through the conductors F , F^1 , and F^2 will be closed and the lamps f , f^1 , and f^2 brought into operation, and so on, the lamps being brought into operation in any one of the various combinations of four, three, two, or one, when any one of these combinations is required, by rotating the circuit closing arm on the pivot C until the proper contact or contacts on its under side is or are brought into engagement with the appropriate contact or contacts on the rings B , B^1 , B^2 , B^3 , when the required circuit or circuits through the conductors F , F^1 , F^2 , and F^3 , will be closed and the operation of the lamp or lamps answering to it or them thereby effected.

To provide for bringing any required number of lamps into operation when desired, the contacts in the rings B , B^1 , B^2 , and B^3 are arranged in radial lines which extend at the proper distance apart from the inner to the outer ring, with the contact or contacts necessary to the operation of one particular number of lamps disposed in one radial line, while those necessary to the operation of another number of lamps is or are arranged in another, and so on, the contacts necessary to the operation of each particular number of lamps that is or are to be operated being disposed in a single radial line. With the contacts in the rings B , B^1 , B^2 , B^3 arranged as above explained, a disk H is preferably employed, which, fixedly secured to the upper end of the stud C, extends outwardly over such contacts and rings, with its outer edge inclined downwardly and provided on its outer surface with a series of numerals, which are so disposed thereon as to bring each individual numeral thereof into line with one or another of the radial lines of contacts, as shown. As thus constructed and equipped, this disk not only serves as a cover for the rings B , B^1 , B^2 , and B^3 and the respective contacts carried by them, whereby to prevent persons from collision with them when the rings are carrying a current or otherwise, but it also serves as an index to indicate the position to which the circuit closing arm must be moved to bring into operation any particular number of lamps that may be required.

With the index thus provided the bringing of any required number of lamps in operation is effected by simply swinging the circuit closing arm D on the stud C until its outer end is brought opposite to the numeral of the index appropriate to that number of lamps, when the arm will engage with the contacts on the ring or rings connected with that particular lamp or with those particular lamps, closing the circuit or circuits through that ring or those rings and thereby the

operation of the lamp or lamps will be effected. In order therefore to aid in determining the exact distance to which the circuit closing arm must be swung to cause the operation of any required number of lamps, this arm is preferably provided on its upper surface with a pointer d^a , which extends inward over the downwardly inclined outer edge of the disk H, with its outer pointed end in close relationship to the numerals of the index, as illustrated in Fig. 1.

For securing the disk H to the upper end of the stud C various means may be employed. I prefer however to employ for this purpose a bolt I, which, passing downward through the center of the disk and through the stud, is provided at its lower end with a nut I^1 , suitable strips of insulating material i , i^1 , i^2 being respectively interposed between the disk, the exterior of the bolt, and the nut, on the one hand, and the stud on the other, whereby to afford insulation to the disk and bolt therefrom. The same will also be the case when the base A is constructed of wood or other similar material and suitable strips of insulating material will be interposed between both the stud C and nut i , and the base, as shown in Fig. 7.

By the construction and arrangement of the parts above described, an electric switch is provided, which, while capable of bringing into and carrying out of operation any required group or number of lamps that may be required, is, at the same time, simple in construction and convenient in operation.

While in the drawings I have shown and in the foregoing described a construction in which four rings B , B^1 , B^2 , B^3 , are employed, it is to be understood that this is merely illustrative, and that a greater or less number of these rings may be employed as a greater or less number of lamps are to be operated. Again, while I have shown and described both the rings and the circuit closing arm as provided with contacts that are constructed in the form of projections, and which is the construction I prefer in practice, it is to be understood that these projecting contacts may be omitted from the circuit closing arm and the parts so related that the under surface of the arm may engage with the contacts of the rings, when it is passed over them, and the switch operate with equal efficiency. Still again, it is obvious that the switch may be modified in other respects without departing from the spirit of the invention.

Having now described my invention, and specified certain of the ways in which it is or may be carried into effect, I claim and desire to secure by Letters Patent of the United States:—

1. The combination, with a plurality of electricity conducting rings that are sev-

erally adapted for connection in circuit with an electric lamp or lamps and having contacts projecting from the face of each, and a base upon which the rings are supported 5 the one within the other with the contacts on the several rings disposed in radial lines and in various orders, of a stud arranged centrally with respect to said rings, a circuit closing arm rotatively mounted on said 10 stud and extending outwardly across the series of rings with its under side disposed in proper relationship to the contacts on such rings to engage with them when swung over the same, a disk extending outward over 15 said rings and contacts secured to said stud and provided near its outer edge with an index for coöperating with the circuit closing arm, and means by which the circuit closing arm may be connected in circuit with a 20 source of electric supply, substantially as described.

2. The combination, with a series of electricity conducting rings B, B¹, B², B³ severally adapted for connection in circuit with 25 an electric lamp or lamps and having contacts projecting from the face of each, and a base A upon which the rings are secured in

concentric relationship to each other with these contacts disposed in radial positions with respect to one another in various orders, 30 of a stud C constructed of electricity conducting material and secured to said base centrally of the rings, a circuit closing arm D pivoted at one end on the said stud and extending outward therefrom across such 35 rings with its under surface arranged to impinge upon the contacts on said rings when swung over them, an insulated cover H secured to the upper end of said stud and extending outward over the series of 40 rings and their contacts with its outer downwardly inclined edge provided with a numerical index for coöperation with the circuit closing arm, and means for connecting the stud C in circuit with a source of electric 45 supply, substantially as described.

In testimony whereof I have hereunto set my hand in the presence of two witnesses this 11 day of October, 1909.

FRIDOLIN W. KURTZ.
